CLAIM

The ornamental design for a waste gas treatment device for radiopharmaceutical synthesis, as shown and described.

DESCRIPTION

1. Waste gas treatment device for radiopharmaceutical synthesis

1.1 : Perspective

1.2 : Front

1.3 : Back

1.4 : Left

1.5 : Right

1.6 : Top

1.7 : Bottom

FIG. 1.1 to FIG. 1.7 show a waste gas treatment device for radiopharmaceutical synthesis according to the present design; The waste gas treatment device for radiopharmaceutical synthesis is used for treating waste gas.
